DESIGN FOR A MERCHANTISE DISPLAY RACK

Warren Wheary, Evanston, Ill.

Application November 7, 1945, Serial No. 123,556

Term of patent 7 years

(Cl. D80—9)

To all whom it may concern:

Be it known that I, Warren Wheary, a citizen of the United States, residing in Evanston, in the county of Cook, State of Illinois, have invented a new, original, and ornamental Design for a Merchandise Display Rack, of which the following is a specification, reference being had to the accompanying drawing, forming part thereof.

In the accompanying drawing illustrating my new design:

Fig. 1 is a perspective view of a merchandise display rack embodying my design.

Fig. 2 is a side elevation of the same.

Fig. 3 is a top plan view of the same.

I claim:

The ornamental design for a merchandise display rack, substantially as shown.

WARREN WHEARY.
